UNITED STATES PATENT OFFICE.

THOMAS E. WORTHINGTON, OF KANSAS CITY, MISSOURI.

HYDROCARBON-FUEL BURNER.

1,350,199.

Specification of Letters Patent. Patented Aug. 17, 1920.

Application filed November 5, 1919. Serial No. 335,914.

To all whom it may concern:

Be it known that I, THOMAS E. WORTHINGTON, a citizen of the United States, residing at Kansas City, in the county of Jackson and State of Missouri, have invented certain new and useful Improvements in Hydrocarbon-Fuel Burners; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to hydrocarbon fuel burners and one of the objects thereof is to provide a fuel burner in which the hydrocarbon will become thoroughly gasified so that complete combustion will take place.

I have provided means whereby the liquid hydrocarbon fuel may be preliminarily heated, if desired, to vaporize it, the vapor being fed downwardly upon a surface, the heat from which will gasify the vapor and means is provided for supplying the requisite amount of oxygen to support combustion so that a very intense flame is provided, and where found desirable, I may utilize a heat-retaining block, preferably consisting of asbestos or mineral wool on account of its known heat absorption and retaining qualities.

In the drawings,

Fig. I is a perspective view of a furnace to which my invention is applied, parts being broken away to show the position of the heater, and

Fig. II is a disassociated view of the several parts of the heater, and

Fig. III is a vertical, longitudinal sectional view through the heater.

Referring now to the drawings by numerals of reference:

1 designates a concavo-convex chamber having a central, upwardly extending, pyramidal or conical projection 2 and provided with a cover 3 with a central opening 4, through which the projection 2 slightly extends. The member 1 is provided with a plurality of air ports 5 consisting of downwardly projecting tubes and said tubes discharge into a central space 6 formed by a cover 7 resting upon the member 1, connected to and spaced from the cover 3, as clearly indicated in Fig. III. The cover 7

preferably carries a seat or pan 8 to receive a heat-retaining block 9 of asbestos or similar material and through which the discharge end 10 of the hydrocarbon supply pipe 11 projects, the discharge end 10 being in axial alinement with the projection 2 and the supply pipe 11 having one or more coils 12 in close proximity to the burner cover 7 so that the heat therefrom will partially vaporize the hydrocarbon as it passes through the pipe and allow it to be discharged in a vapor upon the deflector plate formed by the projection 2, there being a baffle or ring-like flange 13 within the concavo convex member 1 to retard the passage of the oil beyond the base of the projection 2 but in the event that enough oil enters the chamber formed by the members 1 and 3, this will be taken care of by the overflow pipe 14.

From the foregoing it will be apparent that if the valve 15 is opened to admit oil to the inner chamber burner and the same is ignited, the burner will become heated, there being enough oil or hydrocarbon liquid retained by the ring 13 for priming purposes. When the heater becomes hot enough, the hydrocarbon passing through the coil 12 will be vaporized and will be further gasified upon striking the projection 2 and inasmuch as there will be an ample supply of oxygen admitted through the ports 5, an efficient hydrocarbon mixture will be provided to supply an intense heat, as has been clearly demonstrated in actual practice. The arrangement shown in the drawings is such that practically no smoke or soot forms, as the combustion of the fuel is practically perfect and substantially all of the B. T. U. in the fuel are generated into heat available from the burner.

What I claim and desire to secure by Letters-Patent is:

1. In an oil burner comprising a concave bottom having a central, upstanding, conical projection, a baffle ring about the projection, the bottom being provided with air openings, a spider-like top fitting over the bottom and having air ports alining with the air openings, and an oil supply pipe extending through the top of the burner.

2. A burner comprising a base having an upstanding projection, a ring about the projection, said base being provided with openings, a chamber above the base and having tubular ports alining with the ports in the

base, a heat-retaining block carried by the chamber, and a supply pipe projecting through the block and into the chamber.

3. A burner comprising a base having an up-standing projection, a ring about the projection, said base being provided with openings, a chamber above the base and having tubular ports alining with the ports in the

base, a heat-retaining block carried by the chamber, and a supply pipe projecting through the block and into the chamber, said supply pipe having a heating coil intermediate its ends and adjacent to the chamber.

In testimony whereof I affix my signature. 15
THOMAS E. WORTHINGTON.
